(57) **CLAIM**

The ornamental design for a sprinkler, as shown and described.

DESCRIPTION

FIG. 1 is a perspective view of a sprinkler, showing the new design;
FIG. 2 is a front elevation view thereof;
FIG. 3 is a rear elevation view thereof;
FIG. 4 is a right side view thereof;
FIG. 5 is a left side view thereof;
FIG. 6 is a top plan view thereof; and,
FIG. 7 is a bottom plan elevation view thereof.
The broken lines illustrate portions of the sprinkler that form no part of the claimed design.
